[57]

ABSTRACT

The cutter assembly includes a hollow guide track having a slot on an upper side thereof in which a cutting element operates. The cutting element has a handle, a tongue on the handle projecting through the slot, and an enlargement operating within the track of a larger lateral dimension than the slot to lock the cutting element slidably on the track. The cutting element has a blade on each leading edge, such blade being offset to one side whereby to ride along one side edge of the slot and accomplish a shearing engagement against such edge. The invention has a pair of end arms for mounting it on a paper roll holder.

CUTTER ASSEMBLY FOR SHEET MATERIAL

BACKGROUND OF THE INVENTION

This invention relates to new and useful improvements in cutters for sheet material.

Many types of paper or sheet material are supplied in rolls adapted to be removably supported on a holder. In most instances, these holders have tear bars by means of which a selected length of material may be torn off. However, it is difficult to tear an even edge on such tear bars particularly when the roll reaches a smaller diameter and does not have sufficient bulk left to provide a good anchor for tearing off the one end of the paper. In addition, tearing such paper on the bar causes the torn edge to be frayed which in some cases is undesirable.

SUMMARY OF THE INVENTION

According to the present invention and forming a primary objective thereof, the invention provides a cutter having a novel structural arrangement providing for the improved cutting of sheet material.

More particularly the invention provides a cutter assembly having a hollow guide track in which a cutting element operates having blade means capable of efficiently cutting the paper upon movement of the cutting element along the guide track; to provide a cutter assembly wherein the cutting element has its blade means offset to one side thereof for engaging a defining edge of a slot in the guide track for accomplishing a shearing action by the blade; and to provide novel support means for the guide track arranged to detachably connect the guide track to an existing roll holder.

The invention will be better understood and additional objects and advantages will become apparent from the following description taken in connection with the accompanying drawings which illustrate a preferred form of the device.

In the drawings:

FIG. 1 is an end elevational view of the present cutter assembly as mounted on a roll holder;

FIG. 2 is a foreshortened plan view of the cutter assembly, taken on the line 2—2 of FIG. 1;

FIG. 3 is an enlarged fragmentary sectional view taken on the line 3—3 of FIG. 2;

FIG. 4 is an exploded view of a cutting element embodied in the invention; and

FIG. 5 is a sectional view taken on the line 5—5 of FIG. 1.

Referring in particular to the drawings, the numeral 10 designates generally a common type of holder for supporting a roll of paper 12. Such holder may be supported singly on a stand or a number of such holders may be mounted on a rack in order that multiple rolls 12 of paper can be conveniently accessible. In the usual case, the holders 10 have a tear bar 14 with a front edge 16 against which an end of the paper from the roll is physically ripped off. The tear bar 14 is supported on a pair of end arms 18 pivotally connected at 20 to the holder 10 and biased downwardly by tension springs 22 connected between the holder 10 and the arms 18. The outer ends of the arms 18 have apertures 24 and the bar 14 has tongues 26 arranged to project through the apertures, the said apertures being enlarged relative to the tongues to permit the bar 14 to rotatably adjust on the roll as the latter is reduced in diameter.

It is to be understood that the present cutter assembly may be used with other types of holders with a slight alteration of its structure. Basically, the cutter comprises a guide track 30 for a cutting element 32. The guide track 30 comprises a elongated, hollow structure having an upwardly opening slot 34 leading from end to end thereof. The hollow guide track 30 is open at its ends. Such track is supported on the holder 10 by a pair of arms 36 having a hook 38 at one end for engaging aperture 24 in the arms 18. The opposite end of the arms 36 is straight and extends through an aperture 40, FIG. 5, in the guide track 30. Such latter end of the arms 36 is threaded for removably receiving a nut 42. It is thus apparent that upon

removal of the nuts 42 the track 30 may be detached from the arms. Arms 36 may have one or more offset portions 44, FIG. 2, as necessary to support the track 30 on a holder 10. The track 30 is of greater length than the width of the roll 12, and the offset 44 disposes the threaded ends of the arms in an outwardly disposed position relative to the ends of the roll for engaging the track near the ends of the latter. Such arrangement allows the cutting element 32 to be positioned beyond the side edges of the paper, as will be more apparent hereinafter.

10 In a preferred construction, the ends of the arms 36, and more particularly the body portions thereof on opposite sides of the offset 44, are selectively angled such that they cause a frictional binding engagement with the apertures in which they are connected. For example, the threaded ends of the arms 36 extend slightly angularly with relation to the aligned axis of the apertures 40 so that in the normal depending position of the guide track 30 the body portion of the arms 36 at the apertures 40 will frictionally bind in such apertures. Similarly, the hooks 38 at the opposite ends of the arms 36 are angled so that in the depending position of the guide track 30 such hooks have a binding engagement with the arms 18. Such binding engagement at both ends of the arms serves to anchor the guide track against loose mounting and yet by exerting a manual force the hook ends 38 can be dislodged from the apertures 24 when it is desired to remove the cutter assembly. Similarly, the track 30 can be manually forced off the ends of the arms 36 after first removing the nuts 42.

The cutting element 32 comprises a handle portion 46 which in a preferred construction is made up of two parts 46a and 46b, best seen in FIG. 4. These two handle parts are adapted to be secured together by adhesive or the like in their assembly and each has side notches 48 in order that an operator can grasp the handle for manipulation of the cutter.

Depending from the handle portion 46a and having one side surface coextensive with the inwardly disposed surface of such handle portion is a tongue 50 terminating at its lower end in an enlargement 52. In assembled relation of the cutter assembly the tongue 50 projects through the slot 34 in the guide track 40 and the enlargement 52 is contained in the hollow track. Such enlargement is wider than the slot and thus serves to slidably connect the cutter to the guide track. As stated above, the ends of the guide track 30 are open, and upon removal of the guide track from the end arms 36 the cutters are removable out the ends of the guide track.

The tongue 50, although necessarily being quite thin, has a thickened reinforcing central portion 53, FIG. 5. Such thickened portion preferably is rounded so that it will not catch on edges of the paper being cut.

50 Handle portion 46a is provided with a pair of notches or recesses 58 on its inwardly disposed surface on opposite sides of the tongue 50 for receiving cutter blades 60. In a preferred arrangement, the upper edge 62 of the notches is angled upwardly toward the outer ends of the handle portion and the 55 end edges 64 are parallel, the edges 64 which are inwardly disposed being coextensive with the respective side edges 54 of the tongue. The blades 60 have the shape of a parallelogram. An upper angled edge 66 thereof fits along the angled edge 62 of the notches and a bottom angled cutting edge 68 extends from the bottom outer edge of notch 58 to approximately the juncture of the enlargement 52 with the tongue 50, the inwardly disposed upright edges 70 of the blades abutting against respective end edges 54 of tongue 50. The tongue 50 is quite thin at its edges 54, and since the trailing edges 70 of the 60 blades abut against such edges, cut paper edges cannot hang up when the cut is being made.

Tongue 50 is of a length such that the enlargement rides on the bottom of track 30, FIG. 3, and furthermore such that the handle portion 46 is spaced above the track. The blades 60 provide cutting edges entirely through the space between the guide track 30 and the bottom of handle 46 of the cutting element to insure that a good cut will be made. Since the handle portion 46 is out of engagement with track 30, the paper cannot get pinched between the handle portion and the guide track.

As best seen in FIG. 3, the handle portion 46a is of greater thickness than handle portion 46b, and such thickness relationship places the cutting blades 60 in an offset position to one side of the cutter so that the cutting blades ride along one defining edge of the slot 34. Such association of the cutting blades with the one defining edge of the slot provides a shearing action cutting the material. Cutting blades 60 are positively held in the notches 58 by pins 72 engageable in holes 74 in the blades. The handle halves 46a and 46b may be bolted together instead of being secured together adhesively for access to the blades 60 for sharpening. However, the adhesive connection is preferred wherein the blades are permanently attached. In this latter case, a new cutting element may be substituted for the old one when the blades become dull or too the edges of the blades may be filed while in place.

The cutter assembly is installed on the usual paper holder as explained above by engaging the hooks 38 through the openings 24 in the arms 18, or if desired it may be attached to other types of holders simply by minor alteration of the connecting end of arms 36. The guide track 30 hangs by gravity either in surface engagement with the roll 12 or supported away from the roll by engagement of the arms 36 with the holder 10. In a cutting operation, the cutting element 32 is first moved to one end of the guide track and then the length of paper to be cut is pulled from the roll and laid on the top of the guide track. Since the guide track is longer than the roll is wide the cutting element prior to pulling the piece to be cut from the roll can be moved to one end in an out of the way position. Thereupon, the cutting element is merely moved manually across the guide track to shear the paper, the cutting edge of blade 60 which is being used moving along the one defining edge of slot 34 in shearing engagement to cut the paper smoothly and evenly. After finishing a cut, the cutting element is left at the side of completion of the cut and then moved back in making the next cut.

It is to be understood that the form of my invention herein shown and described is to be taken as a preferred example of

the same and that various changes in the shape, size and arrangement of parts may be resorted to without departing from the spirit of my invention.

Having thus described my invention, I claim:

1. A holder and cutter assembly for a roll of sheet material comprising:
  - a. laterally spaced holding means on said holder providing end pivotal support for a roll of paper,
  - b. a pair of end arms attached at one of their ends on said holding means,
  - c. a laterally extending guide track supported on the other ends of said arms,
  - d. said arms being pivotally attached to said holding means at their said one end whereby said guide track is arranged to lie by gravity on the roll of paper with an end of material to be cut from the roll being adapted to lie on the top of said guide track,
  - e. said guide track having a slot on its upper side,
  - f. a cutting element slidably mounted in said guide track,
  - g. said track being of a length sufficient to project laterally beyond each end of the roll and to support said cutter element in end positions beyond each end of the roll,
  - h. said cutting element including a handle portion formed in two parts arranged to be clamped together,
  - i. means depending from said handle portion arranged to project through said slot and guide said cutting element in said guide track,
  - j. and cutter blade means in said cutting element confined between said two handle parts in clamped position,
  - k. one of said handle parts being of thicker dimension than the other whereby said cutter blade means is offset to engage against one longitudinal side edge of said slot to accomplish a shearing cut of the material,
1. said cutter blade means having cutting edges disposed in opposite relation whereby said cutting element is arranged to sever paper in both directions of travel in said guide track.
